UNITED STATES PATENT OFFICE.

EDWARD D. PARKER, OF SALINA, KANSAS.

ELECTRIC COUPLING FOR TRAIN-TELEGRAPHS.

SPECIFICATION forming part of Letters Patent No. 253,419, dated February 7, 1882.

Application filed June 11, 1881. (No model.)

To all whom it may concern:

Be it known that I, EDWARD D. PARKER, of Salina, in the county of Saline and State of Kansas, have invented a new and Improved 5 Electric Coupling for Train-Telegraphs, of which the following is a specification.

The object of my invention is to provide railroad-trains with means for signaling from the cars to the engine, in place of the rope ordinarily used.

The invention consists in circuit-closing couplings by which the cord is connected between the cars, all as hereinafter described.

In the accompanying drawings, Figure 1 is 15 a sectional side view of a locomotive and portions of the front and rear cars of a train fitted with my improved devices. Fig. 2 is a longitudinal section of the coupling-block. Fig. 3 is a longitudinal section in a plane at right 20 angles to Fig. 2. Fig. 4 is an end view of the coupling-block, and Fig. 5 a side view of the same.

Similar letters of reference indicate corresponding parts.

25 Referring to Fig. 1, A is the locomotive, B the tender, and C parts of the front and rear cars of a train, which may consist of any number of cars in addition, either passenger or freight trains.

30 Beneath the locomotive-cab is a battery, D, consisting of a suitable number of cells of the type known as "sealed batteries." The cab also contains an electric bell, E, of ordinary construction, which is in connection with the wires

35 a of a circuit from the battery. The wires a of the electric circuit extend beneath the tender B and cars C to the rear car, where the ends will be connected. The wires a are incased in a covering of wood, by which the wires

40 are insulated and protected from injury. In each car of the train there are wires c d, that are connected to the main wires a, so as to form loops therefrom, and in these loops there are circuit-closers e, which are all to be closed

45 in all except the rear car of the train, in which they are to be left open and press-buttons f placed at convenient places. The circuit-closer on the locomotive is for the purpose of breaking the circuit when the locomotive is not in

50 use.

The coupling devices between the cars, by

which the wires are coupled, are applied in connection with the wooden covering of the wire, as shown most clearly in Figs. 2 and 3. f in those figures is the covering, containing wires 55 a a. The covering is a cylinder formed in two portions attached together, the line of division being lengthwise for convenience of placing the wire. The end of the cylinder is hollowed out and fitted with a projecting tongue, 60 g, of wood or other non-conducting material, the outer end of which is of wedge form. Each wire a terminates with a short spring-metal strip, h, and a separate and longer strip, i. The longer strips i extend upon opposite sides of 65 the tongue g, and are retained out of contact by the tongue, while the shorter springs h are bent into contact, thereby forming a spring-jaw that normally connects the wires a. The tongues g and springs h are so placed that 70 when the ends of two sections are brought together the tongues of one section pass between the springs h of the other section, thus separating them. At the same time the strips i come into contact with the corresponding 75 springs, h, and thus establish metallic continuity of the wires a a. With these arrangements the electric bell on the locomotive will be operated from either car of the train by movement of the circuit-closers or press-buttons. 80

In case the train is separated by breaking of the car-couplings the coupling devices of the electric cord will draw apart, and the springs i, then coming together, will close the circuit and the bell will be operated. This provision 85 for automatically giving an alarm when the couplings separate is especially adapted for use on freight-trains.

When the engines fitted with my device are not in use the switches should be left open. 90 When the circuit is closed the engine-bell will ring continuously and the battery material be quickly used up.

I do not limit myself to the special arrangement and relative location of the devices shown 95 and described, as they may be varied within the scope of my invention.

Having thus fully described my invention, I claim as new and desire to secure by Letters Patent—

In an electric apparatus for signaling on 100 trains, the combination, with the electric wires

a a, of the coupling formed with the springs *h h*, plates *i i*, and tongues *g g*, of non-conducting material, said plates *i* and springs *h* being integral and attached to the wires *a*, whereby, when the coupling is detached, the circuit is closed through the springs *h h*, when coupled electric continuity of the line-wires is secured,

the plates *i i* being separated from each other at all times, substantially as shown and described.

EDWARD DERIAS PARKER.
